5 Figure 1 is a representation of the design of the ornamentation of the handle on one side thereof, and Fig. 2 is a representation of the ornamentation on the other side of the handle.

10 15 The leading feature of the design on the obverse side, Fig. 1, is the representation of geranium leaf, flowers, stems, and buds, grouped as shown, and the leading feature of the design

on the reverse side, Fig. 2, is the representation of "forget-me-not" flowers, stems, and buds in a cluster extending from the leaves, as shown.
